Primary Examiner — Holly H Baynham(74) *Attorney, Agent, or Firm* — Locke Lord LLP; Tim Tingkang Xia, Esq.(57) **CLAIM**

The ornamental design for a backpack with an owl, as shown and described.

DESCRIPTION

FIG. 1 is a perspective view of a backpack with an owl, according to the design;

FIG. 2 is another perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines showing of a backpack are for the purpose of illustrating environmental structures of the backpack with an owl and form no part of the claimed design.
